ATTORNEY

UNITED STATES PATENT OFFICE

WILLIAM A. WEAVER, OF TAMPA, FLORIDA

VIOLIN

Application filed July 19, 1929. Serial No. 379,487.

This invention relates to improvements in violins, an object being to provide a relatively narrow neutral zone which extends longitudinally of the violin, centrally beneath the bridge to provide separate vibration zones upon opposite sides of the neutral zone, to cause the vibrations to start simultaneously from opposite sides of such neutral zone. This action creates sound waves which are divided and travel in opposite directions from a central point, and pass outward through the sound openings of the violin.

Another object of the invention is the provision of means of the above character which in addition, will take the place of the usual base bar; provide clearer and more even tones due to the absence of attachments on either side of the center of the violin; eliminate the necessity of regluing the base bar and the consequent disassembling of the violin for this purpose; increase the strength, durability and artistic appearance of the instrument; provide additional space beneath the tail piece and finger board for cleaning purposes; provide a better footing for the bridge with resultant easier vibration; eliminate the use of gluing for the base bar, glue acting to stiffen the wood and retard vibration; produce increased tone harmony due to unity of wood and grain; provide a wider range of tone regulation by making the instrument more sensitive to vibration; increase the carrying power by eliminating all hindrance to flow of tone through the sound openings; is more subject to light and shade in tone due to its sensitiveness to vibration; prevent screeching noises in bowing; is economical in the use of bow hair due to its sensitiveness to light touch, and in addition, reduce fatigue occasioned by long concerts owing to its sensitive touch.

With the above and other objects in view, the invention further includes the following novel features and details of construction, to be hereinafter more fully described, illustrated in the accompanying drawings and pointed out in the appended claims.

In the drawings:—

Figure 1 is a plan view of a violin constructed in accordance with the invention, the

finger board and tail piece being shown by dotted lines.

Figures 2 and 3 are sectional views taken respectively on the lines 2—2 and 3—3 of Figure 1.

Figure 4 is a fragmentary section showing a slightly modified form of the invention.

Referring to the drawings in detail wherein like characters of reference denote corresponding parts, the body of the violin which is indicated at 10 includes a back 11 and a top 12. The body is shaped after the manner of the usual violin and the top 12 is provided with sound escape openings 13. The finger board of the violin is indicated at 14, the tail piece at 15 and the bridge at 16, these three last mentioned elements being indicated by dotted lines.

As is well known, the violin as ordinarily constructed is provided with a base bar which extends longitudinally within the body and is glued to the top at one side of the center of the violin. This bar sometimes becomes detached and the violin must be taken apart to reglue the bar. In addition, the glue acts to stiffen the wood and render the top of the violin less sensitive to vibration. Further, the bar is located at one side of the center of the top so that the vibratory area of the top upon opposite sides of this bar is uneven or unbalanced, and therefore the sound waves which are created within the tone chamber pass unevenly from the sound openings upon opposite sides of the center of the violin.

These and other disadvantages are overcome in the present invention by providing a groove or recess 17 which extends centrally and longitudinally of the sound board or top 12. For this purpose, the sound board extends inwardly at this point and the walls of this groove or recess take the place of the usual base bar. In addition, this construction reinforces and stiffens the sound board longitudinally and centrally, and not only materially strengthens the instrument, but provides a central neutral zone with separate vibratory zones upon opposite sides thereof. The vibratory action of the zones upon opposite sides of the recess 17 sets up sound waves within the tone chamber, and as the neutral

zone is central of this chamber, these sound waves are evenly produced upon opposite sides of the center of the tone chamber and pass out in equal volume through the openings 13.

5 This construction renders the instrument more sensitive to vibration and produces an even travel of sound waves in opposite directions from a central point and adds materially to the tone quality as well as the volume of sound. By forming the walls of the recess 17 integral with the sound board, increased tone harmony results.

10 If desired, the back 11 may likewise be provided with a similar groove 18 to divide the back into separate vibratory zones.

15 The invention may be applied to old violins by attaching a strip 19 to the inner wall of the sound board and forming a groove 20, as shown in Figure 4 of the drawings, but is preferred to form the walls of the groove integral with the violin structure.

20 The invention is susceptible of various changes in its form, proportions and minor details of construction and the right is herein reserved to make such changes as properly fall within the scope of the appended claims.

25 Having described the invention what is claimed is:—

30 1. In a violin, a trough-like depression extending centrally and longitudinally in the top and bottom walls of the violin to provide a neutral zone and separate vibratory zones upon opposite sides thereof.

35 2. In a violin, a trough-like depression extending centrally and longitudinally of the body of the violin to provide separate vibratory zones.

40 3. In a violin, a trough-like depression extending centrally and longitudinally of the body and formed integral with the top and bottom walls to divide said body into separate vibratory zones.

45 4. In a violin, a sound board having a central longitudinally disposed depression therein tapering at each end and dividing said board into separate vibratory zones.

50 5. In a violin, a sound board having a central longitudinally disposed depression therein dividing said board into separate vibratory zones, the walls of the recess being integral with the sound board, and tapering at each end.

55 6. In a violin, a body having its opposed top and bottom walls provided with a centrally located longitudinally disposed recess.

In testimony whereof I affix my signature.
WILLIAM A. WEAVER.
